(57) **CLAIM**

The ornamental design for an LED ball, as shown and described.

DESCRIPTION

FIG. 1 is an upper perspective view of an LED ball showing the new design;

FIG. 2 is a front elevation view thereof;

FIG. 3 is a rear elevation view thereof;

FIG. 4 is a right elevation view thereof;

FIG. 5 is a left elevation view thereof;

FIG. 6 is a top plan view thereof; and,

FIG. 7 is a bottom plan view thereof.

The broken lines in the drawings are included for the purpose of illustrating portions of the LED ball that form no part of the claimed design.

1 Claim, 7 Drawing Sheets
